(57) **CLAIM**

We claim the ornamental design for a deepwater booster, as shown and described.

DESCRIPTION

FIG. 1 is the front view for a deepwater booster, showing our new design.

FIG. 2 is the left-side view for a deepwater booster, showing our new design.

FIG. 3 is the right-side view for a deepwater booster, showing our new design.

FIG. 4 is the rear view for a deepwater booster, showing our new design.

FIG. 5 is the bottom view for a deepwater booster, showing our new design.

FIG. 6 is the top view for a deepwater booster, showing our new design; and,

FIG. 7 is the perspective view for a deepwater booster, showing our new design.

The dashed broken lines in the drawings represent portions of the deepwater booster that form no part of the claimed design.
